UNITED STATES PATENT OFFICE.

CHARLES RENAUD, OF PARIS, FRANCE.

LOCK.

1,224,021.

Specification of Letters Patent. Patented Apr. 24, 1917.

Application filed November 12, 1913. Serial No. 800,563.

To all whom it may concern:

Be it known that I, CHARLES RENAUD, a citizen of the French Republic, residing at 33 Rue du Repos, Paris, in the French Republic, have invented certain new and useful Improvements in Locks, of which the following is a specification.

This invention relates to a security device in which steel or like balls are used as intermediate operating members for effecting the actuation of all kinds of appropriate locking means such as small pistons, levers, slot and pin mechanisms, links and so on; the said balls being placed into position for 10 effecting the actuation of the locking bolt or the like by means of a key provided with recesses, notches or grooves, the disposition and dimensions of which are capable of unlimited variation, thus permitting of the 15 required safety being obtained.

The use of steel balls, which are manufactured to within a two-thousandth part of a millimeter, permits of the construction of the security device in a simple yet very 20 accurate manner. Moreover, as the balls register directly with the key, the latter can be machined in a very precise manner by boring or turning so that drilling and fitting by filing is avoided, thus considerably 25 simplifying the means of production.

This device, the combinations of which are unlimited can be adapted to pad-locks, locks of all kinds, handles, rings, cloak room apparatus, control apparatus and so on and 30 can be combined with any kind of appropriate closing mechanism, varying with the requirements.

Notwithstanding its simplicity, this device is unpickable while impressions cannot 35 be taken therefrom.

Without diminishing its security the device can be produced in very small dimensions and the keys have the advantage, besides being of small size, of an entire absence of projections or ragged or sharp 45 edges such as are found on ordinary keys.

Several constructional forms of this device are shown, by way of example, in the accompanying drawing, in which:—

50 Figure 1 is a sectional view of a pad-lock fitted with a constructional form of the invention and in which the balls are only operative from one side of the key.

Figs. 2 and 3 show in section and ele-

vation, respectively, the key used for the 55 pad-lock in Fig. 1.

Fig. 4 illustrates diagrammatically in section an arrangement in which the balls are arranged so as to be operative from both sides of the key.

Fig. 5 is a diagrammatic view showing a plurality of combinations to which the device can be adapted.

Figs. 6 to 10 illustrate a plurality of constructional forms of the key.

Figs. 11 and 12 show in longitudinal section and in cross section on the line A—B, respectively, a modification of the invention adapted to a revolving plug for any type of lock.

According to the invention, a suitable number of steel balls 1 of any selected diameter, are housed in corresponding cavities 2 formed at right angles to the longitudinal axis of a core or plug 3 adapted to rotate 75 in a casing 4 which may either constitute the body of a pad-lock (Fig. 1) or the stationary casing of a revolving plug for any kind of lock (Figs. 11, 12). The plug 3 can be retained in the casing 4 by means 80 of a pin 5 inserted through the said casing 4 opposite a groove formed in the plug 3 (Fig. 1) or by means of a projection 6 or a boss formed on the casing, at its ends.

With the balls 1 a flat key 7 coacts, being 85 formed with a number of apertures or recesses corresponding to the number of balls and having an axial distance corresponding to the recesses for the said balls in the plug 3.

The diameter or the depth of these apertures 8 determines the travel which every ball 1 must effect to displace the corresponding locking member which locks the plug and prevents it from rotating. This locking member may be an annular socket 9 (Fig. 1) or a lever 11 (Figs. 11, 12).

Fig. 5 illustrates a ball 1 registering with an annular socket 9, the inner diameter of which is in proportion to the corresponding aperture or recess formed in the key, so that the distance which separates the face of the said key from the external wall of the movable member displaced thereby, is constant for all balls of one and the same combination.

For instance, if the diameter of the ball selected is 3 millimeters and if it is desired

to cause it to occupy, with respect to the key, ten different positions which are illustrated by the series of numerals from 0 to 9 (Fig. 5), it will be seen that if the key is 5 formed with an aperture $27/10$ corresponding to the numeral 9, the ball will enter to the extent of $85/100$ (height of the spherical member). In this case the socket is not perforated. With an aperture of $24/10$ 10 corresponding, for example, to the numeral 6, the ball will enter to the extent of $60/100$; the socket will therefore be perforated at $16/10\frac{1}{2}$ so that the ball enters this socket to the extent of $25/100$; in fact, at this numeral 15 6, the ball is in the key to the extent of $60/100$ only, that is to say it is higher with respect to the admission $85/100$ taken as basis (numeral 9) of $85-60=25/100$.

In any case, the height of the ball 20 mounted by the socket must remain constant. This condition is absolutely indispensable in order that, when the key corresponding to the combination utilized, is in place in the plug, all the sockets should be in line with 25 their rear portion and flush with the external surface of the plug; this is the only position of the sockets permitting of the rotation of the plug.

By means of auxiliary openings formed, 30 on the one hand, in the key, and on the other, in each socket, it is possible to make as many combinations as desired.

The number of possible combinations or arrangements being a function of the number 35 of balls and the number of positions which each ball can occupy with respect to the key, is given by the usual algebraical formulæ of the theory of combinations.

According to the applications, it is possible 40 to use balls of a greater diameter to preserve the same security and either increase the number of combinations (different spherical recesses) or reduce the precision of the machining.

45 This device is applicable to stationary or push revolving plugs.

The balls can be located along one of the generating lines of the revolving plug (Fig. 1, key figures 2, 3), or along a plurality 50 of generating lines opposite or not (Fig. 4, key figures 6, 7).

If these balls are located in planes forming between them angles of 90° , 180° , 270° , the key will be shaped otherwise, for instance, as shown in Figs. 8 and 9.

Finally the balls may be located in a plurality 55 of radial planes forming any desired angles with each other, in which case the key must have a cylindrical outer surface and 60 annular grooves as shown in Fig. 10.

The apertures housing the balls in the plug and in the key may be formed, not along straight lines but along broken or curved lines, which fact would again in-

crease the number of combinations to in- 65 finity.

The preceding devices may be combined with any kind of mechanical movements. The locking members are brought back to their locking positions by the springs 10 70 after the plug has been returned to its initial position and the key retracted therefrom.

For instance, a plug comprising three 75 balls on two opposite generating lines (key figures 6, 7) and supposing that the bolt presents the combination $\frac{6}{7} \frac{4}{3}$, this key will not open any other combination of six balls but only combinations comprising less than six balls and using the same numerals. 80

For example: $\frac{6}{7} \frac{4}{3}, \frac{6}{4} \frac{2}{3}, \frac{2}{3}, \frac{6}{7} \frac{4}{2}, \frac{6}{7} \frac{4}{3}, \frac{4}{2} \frac{1}{3}, \frac{6}{7} \frac{2}{3}, \frac{6}{7} \frac{4}{2}, \frac{6}{4} \frac{2}{3}, \frac{4}{2} \frac{1}{3}, \frac{4}{2} \frac{1}{3}, \frac{6}{7} \frac{1}{3}, \frac{4}{3}$ and so on.

When the key is disengaged from the plug and the same brought back to the position of closure, the sockets 9 are pushed back to the bottom of the housings of the balls by means of their respective springs 10 which are located themselves in corresponding recesses. These springs therefore, follow closely the sockets 9 into the cavities of the latter, so that they constitute locking members either directly by themselves or with the intermediary of an inner or outer sleeve or even by soldering their outer ends together to the socket. 95

In the modification shown in Figs. 11, 12, the balls are combined with levers 11, pivoted at one of their ends to the stationary casing 4 and forming by their opposite end a locking tooth 14 which, penetrating a 100 notch 15 formed in the plug, prevents the latter from rotating when it is in the locking position of the device.

As in the preceding cases, this modification affords the same security against unlocking by the selection of balls entering the key. 105

In this construction, four balls 1 are placed in the cavities 2 of the plug 3 on planes at right angles to one another and situated at different distances from the axis of the plug. The device is constructed in such a manner that in the inoperative position, the balls 1 intersect the axial line of the bolt 3. Anything, however small it may be in section, accompanied with the key, will stop the rotation of the bolt if it is introduced between the balls. The key itself is arranged in such a manner that its recesses bring the balls tangentially to the external surface of the bolt. When it is introduced into the bolt, the key lifts the balls so as to pass, then the balls repelled by the levers 11 controlled by the springs 12, resume a position exactly tangentially to the 120 periphery of the plug if the key used comprises the cavities which respond to the combination adopted for the device. 125

The levers 11 are preferably located, in longitudinal planes of the cavities for the balls. Each of these levers 11 comprises, at a point in its length, corresponding to the ball which it is facing, a projection 13 having a certain height and combining with the depth of the cavity formed in the key wherein the said ball penetrates.

This combination is such, that when the key is introduced in the plug 3, the balls being repelled and resting on the bottom of the cavities of the key, cause the levers 11 to rock in a backward direction, bringing their projections 13 in exact registration with the peripheral surfaces of the plug; at the same time, the stop teeth 14 of these levers disengage from the notches 15 with which the plug is formed, thus permitting of the rotation of this plug by means of the key.

Under these conditions, if a key is used for operating the device, the recesses of which are not of the required dimensions and too deep, for example, the balls do not reach the surface of the plug so that they have not a sufficiently long course to act upon the levers 11 and effect the release of the said plug. On the contrary, if the recesses are not sufficiently deep, the balls project from the surface of the plug and grip against the inner wall of the cylinder, if it is endeavored to rotate the plug.

The plug or mechanism of the lock to which the device is adapted may be of any kind and be actuated either by the plug itself or by the end of the key specially formed for this purpose and projecting at the rear of the plug.

The arrangements hereinbefore described have been given by way of example only, the forms, dimensions, constructional details and applications being susceptible of

variation without deviating from the principal features of the invention.

What I claim and desire to secure by Letters Patent of the United States is:—

1. A lock comprising a casing and a rotary plug in combination with a plurality of locking members each consisting of a plurality of parts, the parts of each member within the plug comprising a hollow cylinder and a ball, the several cylinders being of different internal diameters and interchangeable, the balls being seated in the ends of respective hollow cylinders and being arranged for seating in the recesses of a suitable key.

2. A lock comprising a casing and a rotary plug in combination with a plurality of locking members of the tumbler pin type each consisting of a plurality of parts, the parts of each member within the plug comprising a hollow cylinder and a ball, the several cylinders being of equal lengths and interchangeable, the balls being seated in the ends of respective cylinders and being arranged for engagement by a suitable key.

3. A lock comprising a casing and a rotary plug in combination with a plurality of locking members of the tumbler pin type each consisting of a plurality of parts, the parts of each member within the plug comprising a hollow cylinder and a ball, the several cylinders being of equal lengths and of different internal diameters and interchangeable, the balls being seated in the ends of respective cylinders and being arranged for engagement by a suitable key.

In testimony whereof I affix my signature in presence of two witnesses.

CHARLES RENAUD.
